7 Claims. (Cl. 170—160.2)

1

This invention concerns variable-pitch propellers of the kind in which the blades are capable of adjustment from a positive angle to provide forward thrust to a negative angle to provide backward thrust—hereinafter referred to as reversible pitch propellers.

The object of the present invention is to provide a variable-pitch propeller of the kind referred to in which the pitch of the blades is automatically adjusted within the positive and negative pitch ranges.

According to this invention a reversible, variable-pitch propeller comprises a pitch-change mechanism for adjusting the propeller blades, means for normally limiting the movement of the blades to within the positive pitch-range, a constant speed unit for automatically regulating the pitch-change mechanism in the positive and negative pitch ranges and a manual control for over-riding the constant-speed unit so that it operates the pitch-change mechanism to move the blades to within the negative pitch-range and for simultaneously removing the blade-movement-limiting means.

The manual control is preferably adapted also to reverse the sense of the control effects on the pitch-change mechanism of the constant-speed unit when the control is actuated to bring the blades into the negative pitch-range.

The present invention finds particular application to variable pitch propellers in which the pitch-change mechanism is hydraulically operated for pitch-change movements in both senses in which case the manual control is adapted to bring into operation an over-riding hydraulic motor to over-ride the constant-speed unit and a reversing hydraulic motor to adjust a valve and thereby transpose the ducts from the unit to the pitch-change mechanism.

A practical application of the invention will now be described by way of example, with reference to the accompanying drawings whereof:

Figure 1 is a diagrammatic view, partly in section of the propeller and its control mechanism, and

Figure 2 is a fragmentary view of an alternative construction of a part of the mechanism of Figure 1.

The propeller which is diagrammatically shown in the accompanying drawings is for use on a gas turbine engine in which the propeller, compressor and turbine constitute a common rotary system, the turbine being directly coupled to the compressor and being also coupled to the propeller through a reduction gear. The drive from the

2

turbine to the propeller is not shown in the drawings for the sake of clarity.

The propeller is generally indicated by the reference numeral 5 and is hydraulically operated for which purpose it has a pitch-change motor 6, the ram 7 of which is connected by a link 8, a rod 9 and pin 10 with each of the propeller blades 11.

Hydraulic fluid for the operation of the pitch-change motor 6 is provided by a pump 12 which supplies fluid under pressure to the valve 13 of a constant speed unit, generally indicated by the reference numeral 14. The unit 14 is of known construction and comprises a flyweight governor 15 which is provided to adjust the valve 13. The pressure fluid passes from the valve 13 to the motor 6.

There is also associated with the propeller 5 an electrically-driven feathering pump 16 which is adapted to provide fluid for the operation of the hydraulic motor 6 when the blades 11 are to be moved to their feathered position or returned from said feathered position.

The gas turbine engine is under the control of the pilot, the speed, and hence the power delivered by the engine, being regulated by means of a control 17 in the pilot's cockpit. The power control 17 is connected to a fuel valve (not shown) of the gas turbine engine and is also connected through a suitable linkage 18 with the axially adjustable sleeve 19 of the unit 14.

Movements of the linkage 18 will rotate the gear 20 which meshes with a rack 21 formed on the sleeve 19 so that the latter will be adjusted vertically to vary the datum setting of the constant speed unit by adjusting the loading on the governor spring 22. It will be appreciated, therefore, that when the control 17 is adjusted the quantity of fuel passing to the turbine engine and its speed are both regulated and in this way a desired relationship is at all times maintained between speed and power of the engine. Simultaneously the datum setting of the unit 14 is varied so that it accords with the operating conditions of the engine selected by the pilot; the blades 11 are moved in known manner as the datum setting of the unit 14 is adjusted so that their pitch is made to correspond to the newly selected value of speed.

The control 17 is movable along a slot 23 from one end C corresponding to slow running of the turbine engine towards the position A which corresponds to full power. Intermediate the positions A and C of slot 23 is a gate 25 which allows the control 17 to pass into the slot 24; and thereafter it is movable towards the end B thereof.

The position B of the control 17 also corresponds to the full power of the gas turbine engine.

Whilst the control 17 is within slot 23 the propeller blades are operating within their positive pitch-range so that the propeller thrust is applied to propel the aeroplane forwardly. When the control 17 is in slot 24 the propeller blades are set within the negative pitch-range as herein-after described, and the propeller thrust is applied as a braking force to the aeroplane.

The pump 12 is supplied with oil under pressure from the lubricating system of the turbine engine by a pipe 26. The pressure oil from the pump 12 is delivered to the valve 13 by a pipe 30 and there is a branch 31 from this pipe which leads to a pair of valves 27 and 28. The valve 27 regulates the passage of pressure oil from the branch 31 to a motor 29, whilst the valve 28 regulates the passage of fluid from the branch 31 to a pair of motors 32 and 33.

The motor 29 is connected through a lost motion device 34 with the valve spindle of the constant speed unit 14 the arrangement being that when the motor 29 is brought into operation the unit is overridden in its operation. Accordingly, for convenience the motor 29 will be referred to as the "overriding motor," its control valve 27 as the "overriding valve" and a solenoid 35 which controls the operation of the valve 27 will be referred to as the "overriding solenoid."

The motor 33 is directly connected with the valve 36 which is only brought into operation when it is desired to move the blades from one pitch range to the other during reversing or un-reversing of the blades. For convenience the valve 36 is referred to as the "reversing valve" and the motor 33 and valve 28 will therefore be referred to as the "reversing motor" and "reversing valve" respectively. The valve 28 is actuated by a solenoid 37 which will be referred to hereinafter as the "reversing solenoid."

The reversing valve 36 is urged by a spring 38 to assume a position in which the pitch adjustments are performed under the control of the unit 14 with the blades maintained in the positive pitch-range.

It will be understood that when the reversing motor 33 is brought into operation the pressure fluid which is supplied to it from valve 28 also passes to motor 32. The latter is associated with a relief valve 39 which closes a pipe line connecting the pipes 26 and 30 together. The relief valve 39 is set by spring 40 so that upon a predetermined delivery pressure being exceeded by pump 12 oil passes from the delivery to the suction side of the pump. When the motor 32 is brought into operation it compresses spring 40 and the pressure at which the relief valve operates is increased—for this reason the motor 32 will hereinafter be called the "pressure-increasing motor."

There is associated with the control 17 a two-position switch whose switch-arm 41 is adjustable to engage contact 42 by the control 17 as it is moved through the gate 25 from the slot 23 to the slot 24. Similarly when the control 17 is moved through the gate 25 from the slot 24 to the slot 23 the switch-arm 41 is moved away from contact 42 and brought into engagement with the contact 43.

The solenoid 37 is connected in series with a battery 44 and with contact 42 so that when the switch arm 41 engages this contact the solenoid will be energised. The solenoid 35 is connected in series with the arm of a two-position

switch 45 and in parallel across solenoid 37. The latter is adjusted by a pitch-varying device as later described. The contact 46 of switch 45 is connected to the contact 42 of switch 41 whilst contact 47 is connected with contact 43. With the arrangement described, when arm 41 engages contact 43 and arm 45 engages contact 47 solenoid 35 only is energised. Upon arm 41 engaging contact 42 and arm 45 engaging contact 46 the pair of solenoids 35, 37 are energised.

The arm 45 is adjusted by a slide 48 which is connected to one arm of a bell-crank lever 49 the other arm of which carries a slipper 50 to engage with a circular plate 51 which rotates with the propeller 5. The plate 51 is axially adjustable by means of a rod 52—one of which is associated with each blade 11. The rod 32 is spring urged towards the left and into engagement with a pin 53 carried by the root of the propeller blade 11. The rod 52 and pin 53 constitute a lost motion mechanism so that in the positive pitch-range of adjustment of the blades 11 the pin 53 does not engage the rod 52—the switch 45 cannot, therefore, be actuated. When the propeller blades have reached a fine pitch setting only a little above zero pitch the lost motion is taken up and the switch 45 will be under the control of the propeller. This for instance may occur at a pitch setting of about +5°. As the blades of the propeller are moved into the reverse pitch-range the slipper 48 is adjusted to move the switch arm 45 towards engagement with contact 47. This will occur shortly after the blades have moved into the negative pitch range at say -5°.

When the motor 6 is brought into operation to move the blades 11 through the positive pitch-range towards the negative pitch-range the ram 7 is moved towards the left by pressure fluid from the motor 12 which is fed along the pipe 54 to behind the ram 7. Pressure fluid from pipe 54 also passes along a duct 55 to the right hand end of valve 56. The latter is urged by a spring 57 towards the right. When the ram 7 has set the blades 11 to approximately the zero pitch position a cylindrical extension 58 of the ram 7 engages with a series of circumferentially spaced stops 59. The latter are constituted by enlargements of resilient fingers 60 which are carried by a ring 61. The fingers 60 are designed so as normally to collapse radially inward but are maintained against such movement by an abutment 64 which is capable of axial movement towards the right against spring 62. Such an arrangement of stop for the ram of the pitch-change motor is known and need not be described in greater detail.

When the cylindrical portion 58 of the ram 7 engages the stops 59 the ram is brought to rest but if the pump 12 continues to deliver pressure fluid through pipe 54, the hydraulic pressure within the motor 6 rises. The increased pressure is communicated by conduit 55 to the valve 56 and upon the pressure attaining a predetermined value the valve 56 is moved against its spring 57 towards the left. This permits the pressure fluid to pass through the valve to a passage 63 which leads to the left hand end of the cylindrical abutment 64. The latter is thereupon moved towards the right against the action of its spring 62 and clear of the fingers 59. The latter will therefore collapse radially inwards and permit the ram 7 further movement towards the left to bring the blades to within negative pitch-range.

Subsequently when the blades have been

brought into the positive pitch-range the stops 59 are returned by abutment 64 to lie in the path of the part 58 of the ram 7.

The stops 59 become effective to prevent further movement of ram 7 towards the left when the blades are at zero pitch.

The sequence of operations performed under different flight conditions will now be described. Prior to starting the power plant it is assumed that the ram 7 of the pitch change motor 6 is against the stop 59 (the blades being at zero pitch) and that the control 17 is adjusted to its slow-running position C. The power plant is then started.

For take-off the control 17 is moved to its full-power position A, i. e., with forward thrust, and as a consequence the power plant accelerates. The blades 11 remain at their zero-pitch setting until the speed of the plant exceeds the datum speed for which the unit 14 has been adjusted. Thereafter the blades 11 are adjusted by motor 6 towards a coarse-pitch position until the full power of the engine is absorbed. Whilst the blades 11 are being thus adjusted ram 7 moves clear of the stops 59.

During normal flight, control 17 is adjustable to any position along slot 23 and the pitch of the blades 11 controlled by the unit 14 within the positive-pitch range, the datum setting of the unit being made to accord with the power selected by lever 17.

During the landing approach the power control 17 is adjusted to the minimum power position for landing i. e. to about opposite gate 25, the lever 17 remaining within slot 23. The datum setting of unit 14 will be correspondingly adjusted at the same time and it is arranged that power developed by the engine under these conditions is sufficient to provide only a proportion of the power required to drive the propeller. As a consequence the propeller motors and acts as a windmill to provide the remaining portion of the power. This will have the effect of producing drag thereby preventing the gliding speed of the aircraft from becoming excessive. If the pilot wishes to reduce this drag or to obtain a thrust in the forward direction he suitably adjusts the lever 17 away from its minimum-power position and towards the end A of slot 23.

As soon as the aircraft touches down control 17 is moved through gate 25 from the forward-thrust slot 23 to slot 24 and is then moved to its maximum power position B. During the movement of the power control from the slot 23 to the slot 24 an arm 41 of the associated two-position switch is moved to engage the contact 42. This completes a circuit from battery 44 to solenoids 35 and 37 and both are energised. Actuating solenoid 37 sets valve 28 to pass pressure fluid to motors 32 and 33 and as a consequence the connections from valve 13 to motor 6 are transposed; at the same time the "blow-off" pressure of valve 39 is increased. Actuation of solenoid 35 sets valve 27 to pass pressure fluid to motor 29 so that valve 13 is overridden to direct pressure fluid from pump 12 by pipe 54 to the motor 6; ram 7 is thus urged to the left i. e. to move blades 11 into the negative-pitch range. The motor 32 in adjusting valve 39 permits the pump 12 to deliver at an increased pressure to motor 6 so that valve 56 is opened. The abutment 64 is thus moved to the right allowing stops 59 to fall inwardly—the ram 7 is then free to continue its travel and the blades enter the negative-pitch range.

When the blades have assumed a position cor-

responding to a small negative pitch (at about -5°) the slide 48 of the pitch following device moves arm 45 of its two-position switch on to stud 47 to break the circuit to the overriding solenoid 35. Solenoid 37 remains energised, however, so that the oil duct connections from the valve 13 of unit 14 to the motor 6 remain transposed. The overriding solenoid being de-energised, the unit 14 is free to assume control again and due to its transposition the propeller is able to constant speed within the negative-pitch range.

The amount of braking thrust obtained is controlled by adjusting the position of control 17 along the reverse-thrust slot 24 as its movement away from gate 25 towards the end B of the slot has no effect on the switch 41.

The minimum power position to which the control 17 may be set with reverse thrust is arranged 20 to be not less than that required to maintain the datum speed for which the unit 14 has been set by the control 17. This will ensure that the propeller blades remain within the negative-pitch range. If the power were to be reduced 25 below this value the speed would fall and as a consequence the propeller blades would be moved towards the positive pitch range until this action was stopped by the pitch-following device adjusting switch 45 to energise the overriding solenoid 30 35 once again.

When the landing run is complete the power control 17 is moved to its slow-running position C. In performing this movement arm 41 is set on to stud 43; the overriding solenoid 35 is energised and simultaneously solenoid 37 is de-energised so that the unit 14 is overridden and pressure fluid is directed along pipe 64 to the left hand end of the motor 6 to move ram 7 to bring the blades 11 into the positive pitch range. 40 Finally, the overriding solenoid is cut-out when the two-position switch 45 is actuated by the pitch-following device on the blades being returned to the positive pitch range.

In the modification shown in Figure 2, the unit 45 14 is normally adjusted by the control 17 as described above but in this arrangement it is capable of being overridden in its operation by a manual speed control 70. The latter may be set to three positions one of which (D) corresponds 50 to the normal operation of the propeller 5 when the unit 14 is adjusted by the control 17 in the manner described above. Another position (E) corresponds to a setting of the propeller blades at which the maximum speed of the power plant is obtained and the third position F is selected 55 when it is desired to feather the blades. When the speed control 70 is set to position E or F it overrides the control 17 in adjusting the unit 14. Control 70 is connected with unit 14 by a linkage 60 76 for this purpose.

In contradistinction to the arrangement of Figure 1 the valve 28 controls the passage of pressure fluid to the reversing motor 33 only whilst the valve 27 regulates its passage to both the overriding motor 29 and the pressure-increasing motor 32.

There is associated with the control 70 a switch 71 which is only closed when the control is set to position E. Similarly there is associated with control 17 a two-position switch 72. The latter is actuated by the control 17 in the same manner as described with reference to Figure 1, namely, the switch is adjusted to open one circuit and close another when the control 17 is moved from slot 23 to 24 and vice versa. Switch 71 is con-

nected in series with overriding solenoid 35, battery 44, and a switch 74 associated with a pitch following device generally indicated by the reference numeral 73. One side of switch 72 is connected in series with overriding solenoid 35, battery 44 and another switch 75 associated with the device 73. The other side of switch 72 is connected in series with the battery 44 and with the reversing solenoid 37. The device 73 is operated by the blades 11 through a lost-motion mechanism in the same way as described for Figure 1. The pitch-following device is connected with the switches 74, 75 so that switch 74 is opened when the blades reach a pitch selected for take-off (the take-off pitch) and switch 75 is actuated when the blades are set to a small negative pitch.

When the motor 6 is brought into operation to move the blades 11 from the positive to the negative pitch range the ram 7 is stopped when the blades reach their zero-pitch position as described with reference to Figure 1.

The controls 17 and 70 are interconnected so that the speed control must be moved to its maximum speed position before the control 17 can be moved from slot 23 to slot 24 and further so that control 17 cannot be moved to the slow-running position C whilst control 70 is at its maximum speed position E.

The sequence of operations performed with the arrangement of Figure 2 under different flight conditions will now be described.

Prior to starting the engine it is assumed that the ram 7 is against the zero pitch stop, that the power control 17 is in its slow-running position and that the speed control 70 is in its normal position. The power plant is then started.

For take-off the power control 17 is moved to position A and as a consequence the engine accelerates. The blades 11 remain at their zero-pitch setting until the speed of the engine exceeds the datum speed value for which unit 14 is adjusted whereupon the blades are moved towards a coarse position until the full power of the engine is absorbed.

During normal flight the power control 17 may be adjusted to any position along slot 23 i. e. for forward thrust and the propeller blades are adjustable by the constant-speed unit at settings above the zero-pitch stop.

During the landing approach the power control 17 is moved to lie opposite gate 25, a position corresponding to minimum power for landing. The speed control 70 is thereafter moved to its maximum speed position (E) and as a consequence switch 71 is closed. The effect of this is to energise the overriding solenoid 35 so as to permit hydraulic fluid to enter motor 6 to move the blades 11 towards the negative-pitch range. When the blades are thus moved to a fine pitch setting only a little above zero pitch the pitch-following device 73 is operated to open switch 74 and break the circuit to the overriding solenoid 35. The propeller is then free to constant speed at the maximum speed selected by the manual speed control. Under these conditions the engine power is sufficient to provide only a proportion of the maximum speed demanded by the speed control 70 and as a consequence the propeller must act as a windmill to provide the remaining portion of the power. This will have the effect of producing drag thereby preventing the gliding speed of the aircraft from becoming excessive. If the pilot wishes to reduce this drag or to obtain a thrust in the forward direction

he suitably adjusts the power control lever 17 towards the full power position A.

As soon as the aircraft touches down the power control 17 is moved sideways through gate 25 and is then moved to its maximum power position B with reverse thrust. During the movement of the power control from slot 23 to slot 24 the two-position switch 72 is actuated so that solenoid 35 is again energised; as a consequence the zero-pitch stop is withdrawn and unit 14 is overridden so that the propeller blades are moved to within the negative-pitch range. When the blades have assumed a position corresponding to a small negative pitch the pitch-following device 73 actuates switch 75 to break the circuit to solenoid 35 and to energise the reversing solenoid 37. As a consequence the reversing valve 36 is positioned to transpose the oil duct connections from the unit 14 to motor 6 and the propeller 5 is then free to constant speed within the reverse pitch-range.

The amount of braking thrust obtained is varied by adjusting the position of the power control 17 along slot 24.

The minimum power position to which the power control may be set with reverse thrust is arranged so that the power cannot be reduced below that required to maintain the maximum speed selected by the manual control 70 with a small amount of reverse thrust. This is to ensure that the propeller blades remain within the reverse-pitch range. If the power were to be reduced below this value the speed would fall and as a consequence the blades 11 would be moved towards the positive-pitch range until this action was stopped by the adjustment of switch 75 by the pitch-following device.

When the landing run is completed the speed control 70 is returned to position D and the power control is moved to its slow-running position C. This movement of the power control actuates switch 72 and brings the overriding solenoid 35 into operation to permit pressure fluid to pass to the reversing motor 33 so that the reversing valve 36 is returned to its normal position. Finally, the reversing and overriding solenoids are cut out by switch 75 when the blades are about to enter the positive pitch range; the propeller blades then assume a position ready for taxiing or take-off.

We claim:

1. A variable pitch propeller comprising a hub, at least two blades carried for rotation with the hub and capable of pitch-change movements within a positive and negative pitch range, an hydraulic pitch-change motor, a transmission between the motor and each blade whereby the latter is adjusted by the motor, a mechanical stop to prevent the blades moving into the negative pitch range, an hydraulically-operated means to remove the stop and thereby allow the blades to move into and within the negative pitch range, a pump to supply the motor with fluid under pressure, a constant speed unit automatically to regulate the passage of pressure fluid from the pump to the motor with variations in propeller speed when the blades are in the positive and negative pitch ranges, a valve to reverse the hydraulic connections from the constant speed unit to the pitch change motor, means temporarily to over-ride the constant speed unit to pass pressure fluid to the motor, a manual control to adjust the reversing valve and temporarily to set the over-riding means of the constant speed unit so that the blades are moved to within the negative pitch range and blade-controlled means to re-

set the over-riding means when the blades are brought within the negative pitch range so that the blade pitch is automatically adjusted by the constant speed unit within the negative pitch range.

2. A variable pitch propeller as claimed in claim 1 wherein the mechanical stop is normally effective to prevent movement of the ram of the pitch change motor, said stop being displaceable to permit further movement of the ram to bring the blades into the negative pitch range by an hydraulic motor which is subjected to the pressure fluid in the pitch change motor.

3. A variable pitch propeller comprising a hub, at least two blades carried for rotation with the hub and capable of pitch-change movements within a positive and negative pitch range, an hydraulic pitch-change motor, a transmission between the motor and each blade whereby the latter is adjusted by the motor, a stop to prevent the blades moving into the negative pitch range, and hydraulically-operated means to remove the stop and thereby allow the blades to move into and within the negative pitch range, a pump to supply the motor with fluid under pressure, a constant speed unit automatically to regulate the passage of pressure fluid from the pump to the motor with variations in propeller speed when the blades are in the positive and negative pitch ranges, a valve to reverse the hydraulic connections from the constant speed unit to the pitch change motor, means temporarily to over-ride the constant speed unit to pass pressure fluid to the motor, a manual control to adjust the reversing valve and temporarily to set the over-riding means of the constant speed unit so that the blades are moved to within the negative pitch range and blade-controlled means to reset the over-riding means when the blades are brought within the negative pitch range so that the blade pitch is automatically adjusted by the constant speed unit within the negative pitch range.

4. A variable pitch propeller comprising a hub, at least two blades carried for rotation with the hub and capable of pitch-change movements within a positive and negative pitch range, an hydraulic pitch-change motor, a transmission between the motor and each blade whereby the latter is adjusted by the motor, a mechanical stop to prevent the blades moving into the negative pitch range, an hydraulically-operated means to remove the stop and thereby allow the blades to move into and within the negative pitch range, a pump to supply the motor with fluid under pressure, a constant speed unit automatically to regulate the passage of pressure fluid from the pump to the motor with variations in propeller speed when the blades are in the positive and negative pitch ranges, a valve to reverse the hydraulic connections from the constant speed unit to the pitch change motor, means temporarily to over-ride the constant speed unit to pass pressure fluid to the motor, a manual control to adjust the reversing valve and temporarily to set the over-riding means of the constant speed unit so that the blades are moved to within the negative pitch range, blade-controlled means to re-set the over-riding means when the blades are brought within the negative pitch range so that the blade pitch is automatically adjusted by the constant speed unit within the negative pitch range, said pitch-change motor comprising a movable ram, said mechanical stop being normally effective to prevent movement of said ram, an hydraulic motor subjected to the pressure fluid in the pitch-

change motor for displacing said stop to permit further movement of the ram to bring the blades into the negative pitch range, a relief valve for limiting the pressure of fluid passing to the pitch-change motor, and means for increasing the loading of the relief valve when the manual control is adjusted to bring the over-riding means into operation.

5. A propeller as claimed in claim 4 wherein 10 the loading of the relief valve is increased by a hydraulic motor.

6. A variable pitch propeller comprising a hub, at least two blades carried for rotation with the hub and capable of pitch-change movements, 15 within a positive and negative pitch range, an hydraulic pitch-change motor, a transmission between the motor and each blade whereby the latter is adjusted by the motor, a mechanical stop to prevent the blades moving into the negative pitch range, an hydraulically-operated means to remove the stop and thereby allow the blades to move into and within the negative pitch range, a pump to supply the motor with fluid under pressure, a constant speed unit automatically to 20 regulate the passage of pressure fluid from the pump to the motor with variations in propeller speed when the blades are in the positive and negative pitch ranges, a valve to reverse the hydraulic connections from the constant speed unit to the pitch change motor, means temporarily to over-ride the constant speed unit to pass pressure fluid to the motor, a manual control to adjust the reversing valve and temporarily to set the over-riding means of the constant speed unit so 25 that the blades are moved to within the negative pitch range, blade-controlled means to re-set the over-riding means when the blades are brought within the negative pitch range so that the blade pitch is automatically adjusted by the constant speed unit within the negative pitch range, hydraulic means for adjusting the over-riding means and the reversing valve, solenoid-operated valves for controlling the pressure fluid to the hydraulic motors, and switches for controlling the solenoid-operated valves and being 30 adjusted by the manual control and by the blade-control means.

7. A variable pitch propeller comprising a hub, at least two blades carried for rotation with the hub and capable of pitch-change movements 35 within a positive and negative pitch range, an hydraulic pitch-change motor, a transmission between the motor and each blade whereby the latter is adjusted by the motor, a mechanical stop to prevent the blades moving into the negative pitch range, an hydraulically-operated means to remove the stop and thereby allow the blades to move into and within the negative pitch range, a pump to supply the motor with fluid under pressure, a constant speed unit automatically to regulate the passage of pressure fluid from the pump to the motor with variations in propeller speed when the blades are in the positive and negative pitch ranges, a valve to reverse the hydraulic connections from the constant speed unit to the pitch change motor, means temporarily to over-ride the constant speed unit to pass pressure fluid to the motor, a manual control to adjust the reversing valve and temporarily to set the over-riding means of the constant speed unit so that the blades are moved to within the negative pitch range, blade-controlled means to re-set the over-riding means when the blades are brought within the negative pitch range so that the blade pitch 40 is automatically adjusted by the constant speed

11

unit within the negative pitch range, said manual control being the throttle control of the engine which drives the propeller and is also the datum setting control of the constant speed unit.
